(57) **CLAIM**

The ornamental design for a hand attached coax cable connector, as shown and described.

DESCRIPTION

FIG. 1 is a front perspective view of a hand attached coax cable connector showing my new design;

FIG. 2 is a rear perspective view thereof;

FIG. 3 is a side elevation view thereof;

FIG. 4 is a front elevation view thereof; and,

FIG. 5 is a rear elevation view thereof.

The broken line showing of the environment is for illustrative purposes only and forms no part of the claimed design.
